UNITED STATES PATENT OFFICE

JOHN O'FALLON CLARK, OF UNIVERSITY CITY, MISSOURI, ASSIGNOR, BY MESNE ASSIGNMENTS, TO AMERICAN MANGANESE STEEL COMPANY, A CORPORATION OF MAINE

REPLACEABLE THIMBLE POINT DIPPER TOOTH

Application filed November 25, 1929. Serial No. 409,558.

This invention relates to dipper teeth comprising a base fashioned in a known manner to adapt it to be riveted in place upon the digging front of a dipper or similar excavating implement, and a point embodying that portion of the tooth which wears away more rapidly than the base and which, for the sake of economy, is separately formed and replaceably mounted upon the base; and particularly dipper teeth of the type in which the replaceable point embodies in its construction a socket or cavity which adapts it to fit upon the forward end of the base after the manner of a cap or thimble, and in which the assembling socket comprises upper and lower divergent walls and a pair of side walls, and the point is secured on the base through means of an attaching shank extending rearwardly from one of the divergent walls.

The object of the present invention is to provide an improved form of attaching or anchoring means for a thimble-shaped point or cap point of the kind described; one in which the anchoring shank will extend from one of the divergent walls of the point and form a part of and assist in withstanding abrasive force encountered by one face of the tooth; one in which the attaching means rather than the shear resistance of rivets will act to withstand the weaving tendency of the point under lateral stresses; and one in which attachment and release of the point will be very simple and convenient with the tools available to the operator in the field of use.

Accordingly, the invention proceeds upon the principle of having an anchoring shank or tang extending rearwardly from one of the divergent walls of the point, and adapted to the tooth base in a manner to form a portion of the exposed surface of the latter, and at the same time having a perforated offset portion entering a recess inclined inwardly and rearwardly in the member of the base upon which it laps in a manner to interlock therewith against lateral displacement, and at the same time bring the perforation of the offset portion of the shank into registry with a transverse pin-hole through the base member so that a locking pin may be passed through the parts to resist unintended re-

moval. Incidentally, the locking pin may be a simple member of sufficiently ductile material to have its ends easily bent over in a manner to resist its unintentional withdrawal, and the ends of the opening through the walls of the recess through which the pin is passed may be enlarged to facilitate this manipulation. The offset on the anchoring shank is so related to the inclination of the divergent wall of the point which lies opposite the shank that the offset automatically enters the recess in the act of sliding the point upon the base. In the preferred design of the point, the portion of the shank which lies adjacent the point partakes of the full width of the point and constitutes a capping face for that portion of the base upon which the anchoring shank is to be lapped; the width of the shank being, however, reduced rearwardly to meet the offset portion which is laterally restricted sufficiently to avoid undue encroachment upon the transverse dimensions of those portions of the base member that constitute the walls of the recess and this reduced rear portion of the shank being countersunk in the base as a further means to stay the point against lateral weaving movement upon the base.

In the accompanying drawings in which the preferred design of the invention is shown by way of illustration:

Figure 1 is a side elevation of the complete tooth.

Figure 2 is a bottom plan view of the same.

Figure 3 is a section in an irregular plane taken on the line 3x-3x of Figure 1.

Figure 4 is a detail view in section in a plane indicated by the line 4x-4x of Figure 1; and

Figure 5 is a perspective view of the point detached.

1 represents a known type of tooth paste comprising upper and lower front embracing members 2, 3, and 4 represents a separately formed point replaceably mounted upon said base 1. In order to mount the point 4 upon the base 1, the base is provided with a tapered nose 5 which may be sharply reduced in transverse dimensions from the adjoining portion of the base so as to leave an offset 6; 100

and the point 4 is provided with a receiving socket 7 conforming to the nose 5 and wedging thereon by a rearward longitudinal movement of assembly in a manner to resist displacement of the point upon the base, either vertically or laterally under stresses encountered in service.

To firmly anchor the point 4 upon the base 1 and maintain the wedging fit between them 10 point 4 has, extending rearwardly from one of its divergent faces, a plate-like shank 8 that is preferably coextensive with the point in lateral dimension and with the socket 7 in thickness; and this shank 8 extends rearwardly 15 in overlapping relation to one portion of the base 1, for instance, the under portion, and terminates in an inwardly offset lug or eye 9 having a perforation 10 for receiving a securing pin in a horizontal plane or at 20 such other substantial angle to the vertical longitudinal plane of the tooth as will enable the tooth to resist displacement of the shank, and therefore of the tooth. Perforated lug 9 enters an upwardly and rearwardly inclined 25 recess 11 formed in that member of the base 1 upon which it is desired to have the shank 8 lap, and brings the eye 10 of the lug into registry with the pin-hole 12 extending through that portion of the shank which 30 provides the side walls of the said recess. That portion of the shank 8 which carries the lug 9 is of reduced width, being defined preferably by converging edges 8a, and this reduced portion of the shank is counter-sunk 35 within the face of the base upon which the shank laps, through means of the enlarged base portion 11a of the recess 11. In this way a very substantial interlock between the shank and the base is secured in the direction of lateral stresses that would tend to 40 cause weaving action of the point upon the base; moreover; avoidance of abrupt changes in transverse dimension between the lug 9 and the socket of the tooth reduces liability to 45 breakage.

The forward wall 14 of recess 11 is substantially parallel with that one of the converging upper and lower faces of the tapered nose 5 which is remote from the anchoring 50 shank 8, so that perforated lug 9 and the countersunk portion of the shank 8 enter the portions of the recess 11, 11a designed to receive them, by a rearward and inward movement substantially parallel with the said remote face of the tapered nose.

The ends of the pin-hole 12 are enlarged in a direction transverse to the axis of the pin, as suggested at 15, in order to facilitate deflecting an end or ends of the pin 13 in a manner to resist unintentional displacement of the pin, and at the same time to facilitate use of a wedge beneath the deflected end in straightening up the pin and bringing it 60 within control of the hammer when it be- 65

comes necessary to remove the pin and replace the point.

Such, in detail, is the particular design selected for the purpose of illustrating the invention. In the selected embodiment, the attaching shank 8 is shown as lapsing upon the bottom member 3 of the base; but obviously a design of the invention, in which this attaching shank with its countersunk portion 7a and offset perforated lug are fitted to the upper member of the attaching base, would involve merely a reversal of the parts in case it should be desired to use the shank to resist wear of the upper surface of the base.

I claim:

1. In an excavating tooth, a base having a point receiving nose constructed with converging upper and lower surfaces, one of which has a point-anchoring recess, a point having a socket defined by upper and lower walls which converge in correspondence with the converging surfaces of the nose, and side walls which embrace the nose laterally, and an attaching shank extending rearwardly from one of the converging walls of the socket and constructed with an anchoring lug that extends into the recess of the base; said recess in the base receiving not only the anchoring lug but also a portion of the attaching shank, and the walls of said recess abutting the attaching shank laterally.

2. A tooth as described in claim 1, in which the recess receives the lug and shank by a movement substantially parallel with that one of the converging surfaces of the nose which is remote from the attaching shank.

3. In an excavating tooth, a base having upper and lower converging faces defining a vertically tapered front end, a point having a correspondingly tapered socket defined in part by upper and lower divergent walls, and an attaching shank in the plane of one of said divergent walls having its forward portion adjacent its socket, relatively wide, and adapted to overlie one of the converging faces of the base, and having upon its rear portion an integral lug offset inwardly from said attaching shank, of materially less transverse dimension than the tooth and in a vertical longitudinal plane which lies inwardly from the sides of the tooth; said shank being tapered in width from its portion adjacent the socket to the portion which carries said lug; and said base having a recess positioned to receive said lug.

4. As a new article of manufacture, a point for digging teeth comprising a socket portion defined in part by upper and lower converging walls, and an anchoring shank forming a rearward continuation of one of said walls, having a portion adjacent said socket relatively wide but tapered therefrom toward its rear end and having mounted upon its said rear end an anchoring lug, relatively re-

duced in width and offset from the plane of said shank.

5 5. A tooth point as described in claim 4 in which the anchoring lug has a forward face inclined upwardly and rearwardly in the same general direction as that one of the converging walls of the socket which is remote from the anchoring lug.

10 6. As a new article of manufacture, a tooth point having upper and lower converging walls defining two faces of a socket, with an anchoring shank forming a rearward continuation of one of said walls and terminating in an anchoring lug offset from the plane 15 of said shank; said shank having laterally presented faces converging rearwardly toward said lug and providing surfaces through which it is adapted to abut against confining faces on a tooth base.

20 Signed at St. Louis, Missouri, this 8th day of November, 1929.

JOHN O'FALLON CLARK.
